CLIP FOR HOLDING CANS

Samuel C. Brown, Santa Monica, Calif.

Continuation of abandoned design application Serial No. 45,389, March 21, 1957, which is a continuation of abandoned design application Serial No. 39,136, December 2, 1955. This application February 6, 1958, Serial No. 49,531

Term of patent 14 years

(Cl. D58—26)

Fig. 1

Fig. 2

This application is a continuation of my application Serial No. D. 45,389, filed March 21, 1957, of the same title, now abandoned, which application was a continuation of my original application of the same title, Serial No. D. 39,136, filed December 2, 1955, now abandoned.

I claim:

The ornamental design for a clip for holding cans, substantially as shown.
